KARL VÖLLER, OF DUSSELDORF, GERMANY, ASSIGNOR TO RHEINISCHE METALL WAAREN- UND MASCHINENFABRIK, OF DUSSELDORF- DERENDORF, GERMANY, A CORPORATION OF GERMANY.

GUN WITH RECOILING BARREL.

1,059,093.

Specification of Letters Patent.

Patented Apr. 15, 1913.

Application filed November 18, 1911. Serial No. 660,941.

To all whom it may concern:

Be it known that I, KARL VÖLLER, a subject of the German Emperor, residing at 12 Scharnhorststrasse, Dusseldorf, Germany, 5 have invented certain new and useful Improvements in Guns with Recoiling Barrels; and I do hereby declare the following to be a full, clear, and exact description of the invention, such as will enable others skilled in the art to which it appertains to 10 make and use the same.

In guns in which the trunnions are placed near the breech block, the preponderance of the weight of the forward part of the gun 15 has previously been balanced by special counterweights. The present invention dispenses with any special counterweights by causing the recoil of the barrel to move certain other parts forward. Guns with recoiling barrels are known in which the pistons for the running out movement of the barrel move in the opposite direction to the barrel, but this arrangement has only been adopted to suit a particular construction of the running out device and has not been intended 20 to balance the weight of the barrel and of the moving masses. In contrast to these known devices, in the present invention, the masses of the parts moving in the opposite 25 directions are so proportioned, that the center of gravity of the system in the normal position lies near the breech block and its position is maintained practically constant 30 at different elevations as well as during the recoil and run out.

The drawing shows several constructions for carrying out the invention.

Figure 1 is a longitudinal section of an arrangement, in which the brake cylinder 40 of the recoil brake is constructed as a forward moving part. Fig. 2 is a similar section through an arrangement, in which a special run out piston is driven forward by the braking fluid. Fig. 3 is a cross section 45 on the line 3-3 of Fig. 2. Fig. 4 is a longitudinal section of a device by which the brake cylinder also moves forward, but in which the forward movement of the cylinder is brought about by the barrel in a different manner to that shown in Fig. 1. Fig. 5 is a cross section on the line 5-5 of Fig. 4. Fig. 6 is a longitudinal section through a gun with a forward moving brake cylinder in which a third method of communicating

the movement is employed. Fig. 7 is a cross section on the line 7-7 of Fig. 6. Figs. 8 and 9 represent side views in different positions in which a supplemental cradle moves forward on the recoil of the barrel. Fig. 10 is a cross section on line 10-10 of Fig. 9. 60 Figs. 11-19 refer to other modifications of the arrangement in which the brake cylinder or other mass is moved forward during the recoil by hydraulic pressure.

In the construction shown in Fig. 1, the gun barrel *a* recoils in known manner on the cradle *b*, which can be swung into different elevations about the trunnions *d* on the carriage *c*. The trunnions are situated near the breech block when the barrel is in its forward position. The gun barrel *a* is connected at front and rear to the brake cylinder *g* by a draw member *e*, which runs over the roller *f*. The brake cylinder *g* is movable on the cradle, while the brake piston 75 rod *h* is fixed to the after end of the cradle. On the recoil of the barrel the brake cylinder *g* is drawn forward, and in doing so compresses the spring *i*. The mass of the brake cylinder is so proportioned in relation to the recoiling mass of the gun barrel, that the center of gravity lies near the trunnions *d* and remains there during the recoil of the barrel *a* and the forward movement of the brake cylinder *g*. This has the advantage 85 that the gun is more stable, on being fired, than one in which the whole mass recoils. At the end of the recoil movement, the spring *i* returns the brake cylinder and causes the barrel to move forward. 90

In the construction according to Figs. 2 and 3 a weight is moved forward by hydraulic pressure as the barrel recoils. In this arrangement one of the two upper cylinders shown, acts as a brake cylinder for 95 the recoil; a piston connected to the barrel slides in this cylinder. In the other upper cylinder, a piston also moves with the barrel and during the recoil forces fluid from the upper to the lower cylinder, so as to 100 drive a weight forward. The two pistons connected to the barrel are arranged side by side. The fluid in this case takes the place of the member *e* of Fig. 1. The barrel *a* is connected with the brake piston *k*, which recoils with the barrel in the fixed brake cylinder *l*. This causes the forward movement 105 of a heavy piston *n* in a cylinder *m* con-

5 nected with the brake cylinder l ; the movement of the piston n compresses the air within the cylinder m . At the end of the recoil, the compressed air drives the piston n back and by means of the fluid inclosed between n and k moves the barrel forward. The small bore or cylinder m connected with the cylinder m is for the purpose of enlarging the air space without elongating the 10 cylinder.

10 The construction shown in Figs. 4 and 5 agrees with Fig. 1 in that the brake cylinder g moves forward, when the barrel recoils. But in this case the movement is transmitted 15 by a toothed rack o fixed to the barrel, which on the recoil rotates a pinion p journaled in the cradle and this pinion engages with rack teeth on the brake cylinder g and moves it forward during the recoil of the barrel.

20 In the construction, according to Fig. 6 the barrel a is provided with a screw threaded rack q which engages with a nut r . The latter is provided with a worm on its outer circumference, which gears with the teeth 25 of the rack attached to the barrel. The nut is secured in the cradle b against axial displacement, and has a worm thread in its central opening which engages with an external thread on the brake cylinder g . The 30 latter is provided with a projection sliding in a groove s which prevents the cylinder from rotating. On the recoil of the barrel the nut r is rotated and the brake cylinder g moved forward by the screw thread, so as 35 to compress the spring i . At the end of the recoil, the spring i returns the parts to the original position.

40 In the construction shown in Figs. 8-10 a supplemental cradle constitutes the mass moved forward during the recoil. For this purpose the supplemental cradle b can slide in the cradle t , which is attached to the carriage by the trunnions d . The barrel a is provided, as in Fig. 4, with a toothed rack o 45 which gears with a pinion p , journaled in the cradle t and engages with a toothed rack u , which is attached to the supplemental cradle b . On the recoil of the barrel a the supplemental cradle b is moved forward in 50 the cradle t by means of the toothed gearing. At the end of the recoil of the barrel the 55 return spring (not shown in these figures) actuated in known manner and compressed by the recoil, brings the parts back again to their original positions.

60 In the construction shown in Figs. 11 and 12, which is of the same general type as that shown in Figs. 2 and 3, as the piston rod of the piston enters farther into the brake cylinder during the recoil, a corresponding volume of fluid is pressed into a separate container a^2 the piston being provided with longitudinal ports to allow the fluid to pass. As the piston rod is withdrawn from the 65 brake cylinder, the fluid is driven back into

the cylinder by the pressure of a spring acting on the piston a' . If the container a^2 is arranged above the brake cylinder, the spring actuated piston a' is not necessary, and the fluid would flow back into the brake 70 cylinder of its own accord as the piston rod is withdrawn from this cylinder.

In Figs. 11 and 12 the weight b' , which moves forward as the barrel recoils, is constructed to act at the same time as the brake 75 for the run out movement, and for this purpose a rod d' , which is provided with a groove or is cone shaped is inserted in a cylindrical boring of the weight b' . As the weight b' moves forward during the recoil 80 of the barrel it compresses to a greater degree the air in front of it, which was already under pressure, and which acts as a return spring to run out the barrel and during this movement the weight b' slides on the rod d' 85 and a braking action is exerted the liquid escaping either through the grooves in the rod d' or in the annular space between it and the wall of the bore of the piston.

In Figs. 13, 14 and 15 the brake cylinder g' is movable and acts at the same time as a forward moving weight. The braking action on the recoil and run out is effected in the movable braking cylinder g' , which is driven forward by the fluid displaced during the recoil by the piston attached to the barrel. The air compressed in front of the brake cylinder by this movement takes the place of the return spring. The piston rod h' is fixed to the cradle and does not move 90 with the brake cylinder g' . The rod d' screwed into the brake cylinder moves forward with the brake cylinder during the recoil and as it slides in the hollow piston rod h' acts as a brake during the run out. 100

105 The construction shown in Figs. 16 and 17 is similar to that shown in Fig. 13 but the run out is brought about by a return spring instead of by air pressure. The compression cylinder f' is shown in Fig. 16 110 above the braking cylinder and return spring but below them in Fig. 13. The latter arrangement has the advantage that the air space is above, which is preferable, since air always tends to move into the higher 115 parts and to escape therefrom. The arrangement shown in Fig. 16 has the advantage; that the connection k' between the barrel and the piston of the compression cylinder f' can be considerably shorter and 120 consequently can be lighter and more simply constructed. Also the center of gravity of the whole gun as well as of the moving parts is lower, and this adds to the stability of the gun during fire. 125

130 In the three previous constructions the rod for effecting the run out movement is either disposed in the brake cylinder or is inserted in the weight which is displaced forward during the recoil. It is necessary

that the velocity of the barrel should increase slowly on the return movement and become nearly constant shortly before the end of this movement. If the velocity were rapidly accelerated and fell off in a parabolic curve it might happen, that the barrel acquired a greater velocity than the brake cylinder and piston rod or forward running weight actuated by the return spring.

10 The consequence might be, that the barrel, if it was sliding forward in a horizontal cradle, might run on unbraked, or, if it was running out on an inclined slide it might advance by jerks. It is therefore important, that for guns that may be used with large angles of elevation, for which particularly strong return springs are required and in which consequently the velocity may increase rapidly, the braking action on the 20 run out movement should be effected in the piston rod connected to the barrel, and the run out rod should be attached to the base of the compression cylinder. Such a braking arrangement is shown in Figs. 18 and 19.

25 The piston rod x connected with the barrel and the piston is hollow, and at the forward end opens into the atmosphere. On the recoil of the barrel the piston K of the run out rod s' drives out the air in front of it and draws behind it fluid from the compression cylinder z . During the run out of the barrel, the rod s' is withdrawn from the hollow piston rod x which is filled with fluid, and the piston K of the rod s' dis- 30 places the fluid in front of it. This causes a braking action, if the run out rod s' is cone shaped, and a brake ring B is screwed into the piston of the rod x . The farther the rod s' is withdrawn from the piston rod x during the run out movement, the smaller will be the section of the annular channel between the brake ring B and the cone shaped portion of the rod s' , so that the continued throttling of the fluid escaping 40 from the hollow rod x effects the braking during the run out movement.

In all the constructions shown the reaction of the spring or air pressure is exerted against the forward part of the cradle slide. The force of the spring or the air pressure tends to press the barrel, when the gun is fired during the run out, still more strongly against the fixed resistance, which advantageously increases the stability of the 50 gun. In previously known differential recoil guns the reaction is exerted on the rear part of the cradle slide and tends to turn the gun, when fired, about the spade. Also the center of gravity of the gun is not brought so near to the spade as in those recoil barrel guns in which the cylinder or other weights are moved backward during the recoil. The nearer the center of gravity of the whole gun approaches to the spade, 60 the smaller is the arm of the lever, about

which the center of gravity of the gun turns when fired (assuming the turning point to be in the spade). Consequently a gun, in which heavy masses, such as the brake cylinder, are moved forward in the firing position, has a greater stability. The two factors, viz. that the reaction due to the fixed parts is exerted on the forward part of the cradle, and that heavy masses are moved forward on the recoil of the gun, both act to increase very considerably the stability of the gun, when fired. In addition also in the case of guns with return springs, the center of gravity of the gun as well as the center of gravity of the moved masses is lower, than in the usual type of gun with recoiling barrel.

Having now particularly described and ascertained the nature of our said invention and in what manner the same is to be performed, we declare that what we claim is:

1. A gun having, in combination, a barrel designed to recoil when the gun is fired, and means for moving forwardly when the barrel is moved rearwardly for maintaining the center of gravity of the gun practically constant in all positions of the barrel.

2. A gun having, in combination, a barrel designed to recoil when the gun is fired, and means connected to the barrel for moving forwardly when the barrel is moved rearwardly for maintaining the center of gravity of the gun practically constant in all positions of the barrel.

3. A gun having, in combination, a barrel designed to recoil when the gun is fired, means for moving forwardly when the barrel is moved rearwardly for maintaining the center of gravity of the gun practically constant in all positions of the barrel, and means for braking the run out of the barrel.

4. A gun having, in combination, a barrel designed to recoil when the gun is fired, means for moving forwardly when the barrel is moved rearwardly for maintaining the center of gravity of the gun practically constant in all positions of the barrel, and a spring placed under tension during the recoil of the barrel for effecting the run out of the latter.

5. A gun having, in combination, a barrel designed to recoil when the gun is fired, means for moving forwardly when the barrel is moved rearwardly for maintaining the center of gravity of the gun practically constant in all positions of the barrel, a spring placed under tension during the recoil of the barrel for effecting the run out of the latter, and means for braking the run out of the barrel.

6. A gun having, in combination, a barrel designed to recoil when the gun is fired, and a weighted body for moving forwardly when the barrel is moved rearwardly for maintaining the center of gravity of the gun.

practically constant in all positions of the barrel.

7. A gun having, in combination, a barrel designed to recoil when the gun is fired, a cylinder for moving forwardly when the barrel is moved rearwardly for maintaining the center of gravity of the gun practically constant in all positions of the barrel, a spring acting on said cylinder and designed to be placed under tension during the recoil,

and a piston within said cylinder for exerting a braking action on the run out of the barrel.

In testimony whereof, I have signed this specification in the presence of two sub-^{1b} scribing witnesses.

KARL VÖLLER.
